UNITED STATES PATENT OFFICE

143,414

DESIGN FOR A PORTABLE BAR OR SIMILAR ARTICLE

Signa N. Erickson, Pasadena, Calif.

Application April 5, 1945, Serial No. 118,862

Term of patent 14 years

(Cl. D33—19)

To all whom it may concern:

Be it known that I, Signa N. Erickson, a citizen of the United States, residing at Pasadena, in the county of Los Angeles and State of California, have invented a new, original, and ornamental Design for Portable Bar or Similar Article, of which the following is a specification, reference being had to the accompanying drawings, forming a part thereof.

Referring to the drawings:

Figure 1 is a top plan view of a portable bar or similar article showing my new design;

Figure 4 is a view in front elevation of the bar of Figure 1 but showing portions of the device moved to their respective open positions;

The rear portion of the bar is substantially plain and unornamented.

I claim:

The ornamental design for a portable bar or similar article, substantially as shown and described.

SIGNA N. ERICKSON.
